INTERLOCKING SWITCH FOR ELECTRIC
HEATERS

Alfred J. Huck, St. Louis, Mo., assignor to Knapp-Monarch Company, St. Louis, Mo., a corporation of Delaware

Application January 20, 1947, Serial No. 723,069

6 Claims. (Cl. 219—20)

1

My present invention relates to a switch for controlling a plurality of electrical appliances such as stove plates or the like, wherein parts of the switch are so interlocked mechanically that a maximum wattage is not exceeded in any possible combination of energization for the different appliances, yet each one under certain conditions can be energized with more than its proportionate share of current.

One object of the invention is to provide a switch of this general character which is simple in construction and can be readily fabricated, the assembled switch being comparatively inexpensive and simple to connect into circuits of the appliances controlled, thereby minimizing the number of circuit connections between the switch structure and the heating elements.

Another object is to provide a plurality of switch units, one for each appliance, the switch units being interlocked mechanically as by means of switch operating cams so that upon adjustment of the switch structure to a position for maximum current in one appliance, there will be no possibility of more than a predetermined lesser amount of current available for the other appliance or appliances so that the total wattage drain on the supply wires is within a safe maximum wattage rating.

A further object is to provide a switch structure designed specifically for two heating units as in an electric stove or the like, wherein "high," "medium" and "low" heats can be provided for one burner, and "high," "medium" and "low" heats may also be provided for the other burner, the switch structure being so designed as to permit no more than a "high" and a "medium" combination of the two burners as a maximum available current supply for both burners and prevent any possibility of "high" heat to both burners or "high" heat to one and "medium" heat to the other.

Still a further object is to provide a pilot light means to indicate the "high," "medium" and "low" settings for the two burners, so that the operator knows at all times at what degree of heat both burners are operating.

An additional object is to provide the pilot light means in the form of a pair of bulbs and a single indicator lens for each burner.

Another additional object is to provide a modified arrangement for operating a single neon or other type of electric pilot light for each burner, together with a ballast coil arrangement which permits the single light to be illuminated with three different degrees of intensity, thus simpli-

fying the pilot light arrangement and wiring due to the use of one bulb instead of two.

With these and other objects in view, my invention consists of the construction, arrangement and combination of the various parts of my device whereby the objects contemplated are attained, as hereinafter more fully set forth, pointed out in my claims and illustrated in the accompanying drawings, wherein:

10 Fig. 1 is a front elevation of an interlocking switch structure embodying my present invention showing it mounted on the front wall of a stove, or the like, showing in dotted lines the pilot lights back of the front wall, and showing a cam for the medium wattage elements in dotted lines.

Fig. 2 is a plan view of Fig. 1 showing the front wall of the stove in section.

Fig. 3 is a sectional view on the line 3—3 of Fig. 20 showing the dotted cam of Fig. 1 in full lines and a second cam in dotted lines, the second cam being for the low wattage elements.

Fig. 4 is an electro-diagrammatic view showing the switch structure, the pilot lights and the 25 left and right hand burners connected together and to a current supply cord.

Fig. 5 is a layout view of the back cam for controlling the low wattage elements and showing the relationship of notches of the cam to 30 numbered stations on the cam.

Fig. 6 is a similar layout view of the front cam for controlling the medium wattage elements.

Fig. 7 is a chart showing the different setting 35 combinations of the interlocking switch, heating conditions of the left and right burners for each combination, and the total number of watts for each combination.

Fig. 8 is a view similar to Fig. 3 showing the switches in closed rather than open position.

40 Fig. 9 is a sectional view partially on the line 9—9 of Fig. 8 showing how the various parts of the switch are stacked on a control shaft with spacers between them, and

Fig. 10 is an electro-diagrammatic view of a 45 modified form of pilot light arrangement.

On the accompanying drawings I have used the reference numeral 20 to indicate a shaft. The shaft 20 is journaled in a front plate 22 and a rear plate 24 of a switch frame, the frame 50 having side plates 26 and 28.

The switch frame 22, 24, 26 and 28 may be mounted on a front wall 30 of an electrical appliance such as a stove, as by means of screws 32 (see Fig. 2). The screws are covered by a 55 panel 34 having a substantially circular dial por-

tion 36. The panel 34 is held in position by tubular sleeves 38 and lock nuts 40, each tubular sleeve having on its outer end an indicator lens 42.

The side plates 26 and 28 of the switch frame are provided with turned flanges 44 on which are mounted two contact brackets 46 for the left and right hand burners which are indicated as LB and RB respectively in Fig. 4.

A supply cord having wires 48 and 50, and a plug 52 for plugging into a service outlet is provided, the wires being connected with terminals 54 and 56 respectively of a terminal block 58. The terminal block is suitably mounted on the stove or appliance. A wire 60 then connects the terminal 54 with both brackets 46 which are shown in the exploded view of Fig. 4 as four brackets.

The left burner LB has a pair of heating elements LL and LM. These reference characters indicate "low" and "medium" heating elements for the left burner. "High" heat is had by energizing both heating elements.

For the right burner RB a right "low" element RL and a right "medium" element RM are shown. For the various heating elements four switch blades LL', LM', RL' and RM' are provided, the switch blades being likewise mounted on the flanges 44 of the switch frame. The switch blades and also the brackets 46 are mounted on these flanges as by rivets 62 through suitable insulation plates 64, the plates being secured to the flanges 44 by rivets 66. This arrangement prevents a short circuit between the switch frame and the various brackets and switch blades. The switch blades are connected with their respective heating elements of the left and right hand burners by means of wires 68, 70, 72 and 74 as shown in Fig. 4, and a common wire 76 extending from the junctions between the "low" and "medium" heating elements to a wire 78 that connects with the terminal 56 and the supply wire 50.

For operating the switch blades LL' and RL' I provide a back cam B having lobes and depressions as shown in Figs. 3, 4 and 5. For operating the switch blades LM' and RM' I provide a front cam F having lobes and depressions as shown by dotted lines in Figs. 1 and 3, and in Figs. 4 and 6. The various lobes are adapted to coact with elbows 80 of the switch blades to separate the movable contacts 82 carried thereby from the stationary contacts 84 of the brackets 46 as shown in Fig. 3. When the cams are adjusted to a position where the depressions thereof coact with the elbows 80, then the switches are adapted to be closed as shown in Fig. 8.

The cams have been divided into 26 stations, 1 to 13 inclusive, and 1' to 13' inclusive as shown in Figs. 4, 5 and 6. The dial 36 in Fig. 1 has been similarly divided into 26 stations corresponding thereto. The order of rotation in Fig. 1 is reversed relative to that in Figs. 5 and 6 because the stations in Fig. 1 are for a stationary dial, whereas the stations in Figs. 5 and 6 are for rotating cams as will hereinafter become obvious.

The cams B and F are mounted on the shaft 20 for rotation therewith and for this purpose the cams (which are preferably made of insulation material such as fibre or the like) are provided with central openings 86 having tongues 88. The tongues 88 enter a keyway 90 of the shaft 20 so that the cams are non-rotatable relative to the shaft when threaded thereon. The cams are retained on the shaft together with an indexing disc 92 by means of a lock nut 94 and a plurality

of spacer sleeves 96, 98, 100 and 102 as shown in Fig. 9. The cams, indexing disc, sleeves and nut constitute a rotor assembly. The spacer sleeve 96 bears against a flange 104 of the shaft 20, and the sleeve 102 is shouldered to pass through the plate 24. A cupped spring washer 106 takes up end play and engages the flange 104 with a bearing 108 in the front plate 22 of the switch frame.

The front end of the shaft 20 extends through openings in the front wall 30 of the appliance, see Fig. 2, and the panel 34, and a control knob 110 is mounted thereon. The knob 110 has a pair of stop pins 112 (see Fig. 1) to engage a stationary stop pin 114 of the panel 34 thereby limiting the shaft 20 to slightly less than 180° of rotation, the knob being shown in its counter-clockwise position in Fig. 1.

The indexing disc 92 has a notched periphery, there being a total of 26 notches, although a disc can be made in a 180° sector with only 13 notches. For coaction with these notches a detent roller 116 is provided (see Fig. 3) which is mounted on a pin 118 carried by an arm 120. The arm 120 is pivoted at 122 to the switch frame and a leaf spring 124 is anchored to the switch frame as at 126 for biasing the arm 120 clockwise for the roller 116 to engage in the notches of the indexing disc, thereby definitely positioning the switch at the various stations thereof.

Mounted on each sleeve 38 is a pilot light bracket 128 and supported thereby are pilot lights LLP and LMP for the left burner, and RLP and RMP for the right burner. The lights are connected in parallel to the heating elements LL, LM, RL and RM respectively with a common connection between them to the wires 76 and 78, all as shown by dotted lines in Fig. 4. These wires have not been given reference numerals as it is believed the circuit is clear without referring specifically to them in the description of the operation of the device.

Referring to Fig. 5, the 13 stations on the left half of the cam B are provided with various lobes and depressions which are designed for operating the left burner low heating element LL through the medium of the switch blade LL'. The stations 1' and 13' on the right half of the cam have lobes and depressions for operating the right low heating element RL through the medium of the switch blade RL'. Similarly the stations 1 and 13 of the cam F in Fig. 6 operate the switch blade LM', and the stations 1' to 13' operate the switch blade RM'. The depressions are so located at the different settings 1 to 13 for the upper point of the knob 110 in Fig. 1 that there will be different energization combinations for the left burner and right burner as shown in Fig. 7. In position 1 for instance both burners are off, and there is no current flow. At position 2 the right burner is on "high" and the left burner is on "low." The total wattage is 1600 which has been taken arbitrarily as the maximum safely available from the current supply wires 48 and 50. This total is made up of 1200 watts in the right burner, and 400 watts in the left burner.

The only other combination with "high" for the right burner that does not exceed 1600 watts is "off" for the left burner. This is position 3. Positions 4, 5 and 6 are for "medium" settings on the right burner, and with this setting the "medium" setting of the left burner also is permitted as in position 4, since both the "medium" heating elements are 800 watts each. The cams have

been so designed that there is no possibility of a "high" for the left burner when there is a "medium" for the right burner or vice versa.

When the right burner is on "low," then "high" is permitted in the left burner as at position 1, and to get any other possible combination on the left burner positions 8, 9 and 10 provide for "medium," "low" and "off." This leaves one remaining combination with the "low" of the right burner and that is "off" for the left burner, whereas when the right burner is "off" it may be desirable to have "high," "medium" or "low" in the left burner. This is accomplished by positions 11, 12, and 13 as indicated on the chart in Fig. 7.

It will be noted that the total wattage of any combination does not exceed 1600, yet with each of "high," "medium," "low" and "off" on the right burner there can be had "low" or "off" on the left burner. When there is "medium" on the right burner, "medium" can also be had on the left burner. Thus by designing the cams B and F so that there is no possibility of two "highs," or a "high" and a "medium," the maximum current drain on the wires 48 and 50 at any time does not exceed 1600 watts whereas both burners at "high" heat would require 2400 watts, or one at "high" and the other at "medium" would require 2000 watts.

The foregoing description discloses a comparatively simple mechanical interlock between a pair of very simple switch units so that at no time is a predetermined wattage exceeded, yet in each burner there is a possibility of getting a higher wattage than half the total of the available wattage. The construction is such that it requires no complicated wiring connections, there being but one switch for each heating element involved and no necessity of running one wire to several different connections.

Considering the cams L and R in Figs. 5 and 6, it will be noted that at stations 1 and 1' the cams have lobes, and that at 2 and 2' the cam B has depressions, whereas the cam F at station 2 has a lobe and at station 2' a depression. This causes all four of the switch blades to be in the open circuit positions of Fig. 3 when the knob 110 is at the "off" position (stations 1 and 1' in Fig. 1) whereas when it is moved clockwise to station 2-2' the switch blade LL', RL' and RM' are in the depressions at stations 2 and 2' of Fig. 6 respectively, thus energizing the low heating element LL of the left burner and both of the heating elements RL and RM of the right burner for "high" heat. This is indicated on the chart in Fig. 7 and similarly the other "low," "medium" and "high" heating combinations can be traced out by comparing the chart with the depressions of the cams at the various stations corresponding to the combination numbers in the left hand column. The switch blades will be in the closed circuit positions in the proper order to establish these combinations without at any time having an excessive current drain.

It will be noted that some of the cam depressions have one of their inclines either ahead or rearwardly of the limits of the stations indicated by radial marks in Figs. 5 and 6, and this is for the purpose of preventing any accidental closure of certain contacts that would give a "medium" and "high," or "high" and "high" combination of heating element energizations. In other words, there is a gap between the positions determined by the detent mechanism where all contacts are open to avoid any possibility of overlapping of contacts that might momentarily

throw a load greater than 1600 watts on the line and result in a blown fuse.

With respect to the pilot lights LMP, LLP, RMP and RLP, they are energized when their respective heating elements LM, LL, RM and RL are energized so that the operator can determine whether the burners are energized for "low," "medium" or "high" heat without referring to the dial 36. The pilot lights LMP and RMP are higher candle power than the lights LLP and RLP, so that "medium" heat can be distinguished from "low" heat because of the greater brightness of the lights. When however, both of the "low" heat and the "medium" heat pilot lights are energized then a third degree of light intensity is observable through the lens 42 and this degree is greater than either the "low" heat light or the "medium" heat light when they are energized independently.

It will be noted that the pilot lights LLP and RLP are farther away from the lens 42 than the pilot lights LMP and RMP. This permits the use of pilot bulbs all of the same candle power as distinguished from two different candle powers as outlined in the last paragraph. This arrangement is much better for commercial production because only one type of bulb need be supplied, handled and inserted during factory assembly. The "low" indicating pilot bulbs being spaced farther from the lens than the "medium" pilot bulbs insures a lower degree of illumination for "low" indication than for "medium" indication at the lens 42 and the net effect is the same on the lens as when bulbs of different wattages or candle powers are used for the two different indications.

The use of the pilot lights of course is optional as dial 36 gives an indication as to the setting of each burner and the dial is so arranged that the upper end of knob 110 in Fig. 1 can be used to quickly select "high," "medium" or "low" heats for the right burner; whereas the lower end of the knob then indicates what possible heat or adjustment to "off" position can be had for the left hand burner for any one of the "high," "medium" or "low" heats at the right burner.

While I have described an arrangement wherein the cam B is for low wattage and the cam F is for medium wattage, an alternative arrangement can be provided whereby the back cam B controls the "low" and "medium" heating elements of the left burner, that is, controls LL' and LM'; and the front cam F controls the "low" and "medium" heating elements RL' and RM' of the right burner. In other words, two systems are possible, one in which one cam controls both low wattage elements with the other cam controlling both medium wattage elements as first described and illustrated in the drawings, and the other in which one cam controls both heating element sections of one burner with the other cam controlling both heating element sections of the other burner (as described in this paragraph).

In Fig. 10 I show a modified construction wherein a single pilot light LP is provided for the left burner and RP for the right burner. The heating elements are the same as in the previous figures and accordingly bear the same reference numerals. Switch blades and wires of the circuit corresponding to those in Fig. 4 are also shown. By providing the pilot lights LP and RP of neon type, ballast resistors 128 and 138 may be connected as shown so that at "low" settings for the interlocking switch the "high" ballast resistance 128 is in circuit with the light, where-

as at the "medium" setting a "medium" ballast 130 is in the neon light circuit. At a "high" setting both ballasts are in parallel so as to give a low resistance and consequently a high illumination. Thus with one light for each burner, three different degrees of illumination are possible with three different degrees of energization at each burner.

The pilot lights LP and RP may be of small wattage filament type instead of neon lights, and the ballast resistors 128 and 130 would be accordingly of somewhat lower resistance value to secure the desired results. The arrangement shown in Fig. 10 has the advantage of using half as many pilot lights as the arrangement shown in Fig. 4, and somewhat simplifies the wiring.

From the foregoing description it will be obvious that I have provided an interlocking switch for stoves and the like, wherein it is possible to energize one burner at a higher wattage than half the available wattage for two burners. The switching arrangement is such that there is no possibility of energizing the burners so that wattage exceeds a pre-determined degree such as 1600 watts. Ordinarily two burners could be provided having a wattage rating of only 800 watts each and no interlocking of two switches is required. This is not always adequate, however, to do a good cooking job.

With my arrangement 1200 watts is available on one burner if the cooking requirements are such as to need this high a heat. The total wattage value of 1600 has been used as this is the maximum safely allowable on a 15 ampere fuse such as commonly installed in house wiring circuits. The wattage relationship of course, can be increased or decreased, and varied considerably within the scope of my invention. Two burners have been shown merely by way of illustration, whereas three or more appliances may be controlled by a similar switch having additional cams and switch blades.

The construction and assembly of the switch is comparatively simple and by making the cams of the proper shapes to start with there is no subsequent problem of proper connection of wires to a plurality of switch blades as in other types of switches. One wire to each switch blade is all that is required, aside from the common wires leading to the heating elements and to the brackets 46. When once wired properly, then the switch cams automatically take care of all of the combinations as set up in Fig. 7. The key tongues 88 on the cams F and B insures proper alignment of the cams in relation to each other, and in relation to the detent disc 92 which has a similar keying arrangement. The knob 110 is also keyed properly on the shaft so that the cams rotate through their range of positions slightly less than 180° as limited by the stop pins 112 and 114.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. A switching system comprising a pair of appliances each having a low and a medium heating element, a shaft, a pair of cams connected thereto to operate as a unit, a pair of switches operated by each of said cams, two of said switches

being provided for the low and medium heating elements of one of said appliances and the other two of said switches being provided for the low and medium heating elements of the other of said appliances, said shaft being adjustable to positions for closing said switches in different combinations which combinations include in one position of the shaft the low heating element switches for both appliances, in another position of the shaft the low heating element switch for one appliance and the medium heating element switch for the other appliance, and in still another position of the shaft the low heating element switch only of one appliance when both the low and medium heating element switches of the other appliance are energized.

2. A switching system of the character disclosed comprising a pair of electric burners each having a low and a medium heating element, four switches only electrically connected with said low and medium heating elements of said pair of burners, two cams on one shaft for operating said switches, said cams in one position effecting closure of three of said switches to energize the low heating element of one burner and the low and medium heating elements of the other burner, said cams in a second position effecting closure of two of said switches to energize the medium heating element of each burner, said cams in a third position effecting closure of two of said switches to energize the low heating element of one burner and the medium heating element of the other burner, said cams in a fourth position effecting closure of two of said switches to energize the low heating element of each burner, said cams in a fifth position effecting closure of only one of said switches to energize the low heating element of one burner, said cams in a sixth position effecting closure of two of said switches to energize the low and medium heating elements of only one of said burners, and said cams in a seventh position effecting closure of one of said switches to energize the medium heating element of only one of said burners, said cams in all enumerated positions having their switch operating lobes so related as to prevent energization of both heating elements of one burner when both heating elements of the other burner are energized.

3. An interlocking switching system comprising a pair of electrical appliances each having a low heating element and a medium heating element, a single switch only for each of said four heating elements, and cam mechanism comprising two cams on one shaft for opening and closing said switches in a combination which in one position of the cams closes three of said switches to energize only the low heating element of one appliance when both heating elements of the other appliance are energized to provide high heat, said cams being shaped to prevent the medium heating element of one appliance being energized when both heating elements of the other appliance are energized.

4. A switching system comprising four switches, a pair of burners each having a low and a medium heating element, a pair of cams operable as a unitary structure for operating said switches, said cams in one position closing three of said switches to energize both the low and medium heating elements of one burner and simultaneously therewith only the low heating element of the other burner, in another position closing two of said switches to energize the low or medium heating element of one burner and simultaneously

ously therewith the medium heating element of the other burner or in still another position closing two of said switches to energize the low heating elements of both burners, said cams being so shaped as to prevent the low and medium heating elements of both burners being simultaneously energized.

5. In an interlocking switching system, a pair of heating elements each having a low section and a medium section, a single switch for each of said two sections, and a pair of simultaneously rotatable cams for said switches to close different pairs of them selectively in different positions of the cams to energize the low section of one heating element and the medium section of the other heating element, to close a different pair of said switches to effect energization of the medium sections of both heating elements, or closing different banks of three of said switches to energize both sections of one heating element but the low section only of the other heating element, said cams being so shaped as to prevent both switches for each heating element being closed at the same time.

6. In a switching system, four single normally closed switches, two burners each having a low heating element and a medium heating element, said switches being electrically connected one with each heating element and each having a switch blade, two cams connected together for simultaneous rotation, one cam for each for operating two of said switches, said cam means having

notches receiving said switch blades to close said switches, said notches being arranged in circumferentially spaced relation around the periphery of said cam means to effect closure in one position thereof of two of said switches to energize the medium heating element for both burners simultaneously or at another position thereof closing three of said switches for energizing the low heating element of one burner and the low and medium heating elements of the other burner, said cams being shaped to prevent simultaneous energization of all four of said heating elements.

ALFRED J. HUCK.
